UNITED STATES PATENT OFFICE

122,427

DESIGN FOR A BUMPER

Orson C. Warner, Worthington, Ohio

Application April 15, 1940, Serial No. 91,677

Term of patent 7 years

To all whom it may concern:

Be it known that I, Orson C. Warner, a citizen of the United States, residing in Worthington, in the county of Franklin and State of Ohio, have invented a new, original, and ornamental Design for a Bumper, of which the following is a specification, reference being had therein to the accompanying drawing, forming a part thereof.

Figure 1 is a plan view of a bumper showing my new design, and

Figure 2 is a front elevational view thereof.

Figure 3 is a fragmentary perspective view of the bumper and bracket member taken from the rear, and

Figure 4 is a sectional view taken on the line 4—4 of Figure 2.

I claim:

The ornamental design for a bumper, as shown.

ORSON C. WARNER.
